US00D842398S

(12) **United States Design Patent** (10) **Patent No.:** **US D842,398 S**
(45) **Date of Patent:** **** Mar. 5, 2019**

(54) **BODY SHAPING EQUIPMENT WITH CORD**

(71) Applicant: **Zhejiang Raytheon Technology Co., Ltd.**, Zhejiang (CN)

(72) Inventor: **Xiangjun Zhu**, Zhejiang (CN)

(73) Assignee: **ZHEJIANG RAYTHEON TECHNOLOGY CO., LTD.**, Yongkang, Zhejiang (CN)

(**) Term: **15 Years**

(21) Appl. No.: **29/628,137**

(22) Filed: **Dec. 1, 2017**

(30) **Foreign Application Priority Data**

Aug. 5, 2017 (CN) 2017 3 0354630

(51) **LOC (11) Cl.** **21-02**

(52) **U.S. Cl.**

USPC **D21/673**

(58) **Field of Classification Search**

USPC 482/5, 38, 41, 51, 92, 99, 121, 130, 133, 482/138; 601/23; D21/662, 673, 676, D21/686, 687, 690, 691, 694, 695, 698, D21/797

CPC A63B 22/203; A63B 23/0227

(57) **CLAIM**

The ornamental design for a body shaping equipment with cord, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view of a body shaping equipment with cord showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of the body shaping equipment with cord in use, with the cords in an alternate position;

FIG. 9 is a perspective view of the body shaping equipment with cord in use, with the cords in an alternate position;

FIG. 10 is a top plan view of the body shaping equipment with cord in use, with the cords in an alternate position; and,

FIG. 11 is a perspective view of the body shaping equipment with cord in use, with the cords in an alternate position.

1 Claim, 11 Drawing Sheets
